CLAIM

The ornamental design for a tool mounting bracket with light fixture, as shown and described.

DESCRIPTION

FIG. 1 is a perspective view of the tool mounting bracket with light fixture of the present invention.

FIG. 2 is a front elevation view of the tool mounting bracket with light fixture of the present invention, the rear elevation view being a mirror image thereof.

FIG. 3 is an end view of the tool mounting bracket with light fixture of the present invention, the opposite end being a mirror image thereof; and,

FIG. 4 is a top view of the tool mounting bracket with light fixture of the present invention.

The hood shown in broken lines is for illustrative purposes only and forms no part of the claimed design.
